UNITED STATES PATENT OFFICE.

JOHN L. MATTHEWS, OF BALTIMORE, MARYLAND, ASSIGNOR OF ONE-THIRD TO CHARLES E. BARRY AND ONE-THIRD TO JOHN ROESSER, OF BALTIMORE, MARYLAND.

SMOKE-CLEANER.

No. 824,800.

Specification of Letters Patent.

Patented July 3, 1906.

Application filed February 13, 1906. Serial No. 300,865.

To all whom it may concern:

Be it known that I, JOHN L. MATTHEWS, a citizen of the United States, residing at Baltimore city, State of Maryland, have invented certain new and useful Improvements in Smoke-Cleaners, of which the following is a specification.

My invention relates to an improvement in a smoke-cleaning device, the primary object being, as the name implies, to cleanse the smoke from any stack or chimney of any height, and it is a purpose of my invention to do away with expensive stacks and chimneys on account of the great height required and to provide for an equal or adequate draft without dependence upon the weather, the draft being regulated and controlled by my device. The device is perfectly safe as well as successful in operation.

With these objects in view my invention consists in certain novel features of construction and combinations of parts, which will be hereinafter described, and pointed out in the claims.

In the accompanying drawings, Figure 1 is a view, partly in elevation and partly in vertical section, of my invention organized in operative and demonstrable form. Fig. 2 is a sectional view of a modified form of a down-pipe.

A represents a chimney or stack of ordinary form and of suitable height. On top is a hood or bonnet 1, which hermetically seals the stack or chimney at that point. This hood or bonnet is preferably made of sheet-iron and is provided with the elbow 2 for the inlet and outlet of the smoke. The hood is adapted to be secured in place on the stack or chimney by bands, straps, or other means.

(Not shown.) Smoke from the furnace enters at any convenient point—say through a pipe 3—and is discharged into the chimney or stack. A down-pipe 4 is fastened to the elbow 2 of the hood and extends straight downwardly or in the form of a coil 5, as shown in Fig. 2, discharging into the tank C at or near the bottom of the latter. The tank may be placed on the roof of the building, in the engine-house, yard, or other convenient place.

While the tank may be variously built, it is preferably made of sheet metal after the manner of an upright boiler, provided with a

stack 7 of suitable dimensions and height, which is open at the top, as designated by 8. 55 The tank is made with a solid bottom and in such dimensions as required—say from ten to fifty inches in diameter and from four to ten feet in height, according to the size of the stack—and in the bottom of the tank there should be contained several inches of water. (Not shown.) It is provided at or near the bottom with a small door 9 in the side, out through which the debris, dirt, or sediment that may accumulate may be raked. An 60 outlet-pipe 11 of proper dimensions is located a suitable distance above the bottom of the tank—say just above the water medium—(not shown) for draining off the excess water into the gutter or elsewhere, which may form 70 in the tank by reason of condensing the exhaust-steam therein. A steam-pipe 12 from the boiler extends alongside the stack or chimney and into the hood 1 and terminates with a nozzle 13 inside of the elbow 2, this nozzle 75 being perforated to spray steam into the pipe 4. A second exhaust-steam pipe 15, which is adapted to facilitate in the operation and in the performance of the functions of my improved apparatus, extends into the tank 80 at a point near the bottom and is extended within the tank to a point about the center thereof and then extends upward a suitable distance above the point where the down-pipe 4 enters. On the end of the pipe 15 is a 85 nozzle 16 similar to the one shown in the hood. While the nozzle is provided and shown in both instances, it can be dispensed with without affecting the working of the apparatus.

The action of the steam on the smoke as it passes down through the pipe 4 to the tank C is to wash out the carbon and other visible matter, and as the smoke enters the tank it will be again acted upon by the steam from the 95 spray therein contained and again washed, and the carbon will be taken up by the water in the bottom thereof, and when this greasy water reaches a certain height it will pass out of the tank through the overflow-pipe 11 to 100 the gutter or elsewhere.

By reason of the exhaust-steam being forced into the tank through the pipe 15, the heavy carbon in the smoke in the tank is precipitated down into the water (not shown) in 105 the bottom of the tank, while the gases pass

out through the opening 8 in the stack on the top of the tank, this opening being of sufficient size and the stack of sufficient height to afford an adequate draft. By reason of the 5 outlet of the pipe 15 discharging the exhaust-steam at the point mentioned, which is directly below the opening in the top of the tank, a forced draft is to a certain extent created.

10 A series of boilers of separate plants may be supplied with the apparatus, and the different exhaust-pipes run to one large storage-tank, and the smoke is acted upon in the same manner as in the individual plant.

15 Suitable valves 17 and 18 in the pipes 12 and 15 control the discharge of steam there-through, and 6, 10, and 14 are **L** connections thereon.

It is evident that slight changes might be 20 resorted to in the form and arrangement of the several parts described without departing from the spirit and scope of my invention, and hence I do not wish to limit myself to the exact construction herein set forth; but,

25 Having fully described my invention, what I claim, and desire to secure by Letters Patent, is—

1. The combination with a chimney or stack and a smoke tank or holder provided 30 with an outlet at the top of a smoke-pipe leading from the stack and discharging into the tank or holder, a steam-pipe provided with a nozzle discharging into the upper end of the smoke-pipe, another steam-pipe provided 35 with a similar nozzle discharging upwardly in line with the outlet within the smoke tank or holder above the point where the smoke-pipe discharges therein substantially as described.

2. The combination with a chimney or 40 stack and a smoke tank or holder provided with an outlet at the top, of a circuitous smoke-pipe leading from the chimney or stack and discharging within the tank or holder, a steam-pipe provided with a nozzle spraying 45 and discharging into the upper end of the smoke-pipe, of a steam-pipe provided with a similar nozzle discharging upward in line with the outlet within the smoke tank or holder above the point where the smoke-pipe 50 discharges therein substantially as described.

3. The combination with a chimney or stack and a smoke tank or holder, of a smoke-pipe leading from the chimney or stack and discharging within the holder, a hood or bonnet hermetically sealing the top of the chimney or stack and inclosing a portion of the smoke-pipe, a steam-pipe provided with a discharge-nozzle discharging steam within the smoke-pipe substantially as described.

4. The combination with a chimney or 60 stack and a smoke tank or holder, of a smoke-pipe for conducting the smoke from the chimney or stack to the tank or holder, a hood or bonnet hermetically sealing the top of the smoke-stack and inclosing a portion of the 65 smoke-pipe, a steam-pipe discharging within the smoke-pipe inducing the downward current of the smoke and gases through the smoke-pipe and a steam-pipe discharging within the tank or holder for inducing the 70 precipitation of the heavy carbon contained in the smoke substantially as described.

5. The combination with a chimney or 75 stack and a smoke tank or holder, of a smoke-pipe for conducting the smoke from the chimney or stack to the tank or holder, a hood or bonnet hermetically sealing the top of the smoke-stack and inclosing a portion of the 80 smoke-pipe, a steam-pipe discharging within the smoke-pipe inducing the downward current of the smoke and gases through the smoke-pipe and a steam-pipe discharging within the tank or holder for inducing the precipitation of the heavy gases contained in the 85 smoke, of an open stack on the top of the tank or holder, a door in the side near the bottom thereof for removing the debris and a drain-pipe 11 for draining off the excess of water substantially as described.

6. The combination with a stack or chimney, a smoke tank or holder, and a smoke-pipe leading from one to the other, of a hood or bonnet hermetically sealing the upper end of the stack or chimney and inclosing a portion of the smoke-pipe, of a steam-pipe extending within the elbow, of an elbow connecting the smoke-pipe with the hood, a nozzle on the steam-pipe for directing the smoke through the smoke-pipe to the tank or holder, and means within the tank or holder for precipitating the carbon contained in the smoke and means within the top of the tank to allow the escape of the gases, substantially as 95 described.

7. The combination with a smoke stack or 100 chimney and a smoke tank or holder, of a spiral smoke-pipe leading from one to the other, a hood or bonnet hermetically sealing the top of the smoke-stack and inclosing a portion of the smoke-pipe, and means for discharging steam into the smoke-pipe, substantially as described.

In testimony whereof I affix my signature in presence of two witnesses.

JOHN L. MATTHEWS.
